UNITED STATES PATENT OFFICE.

PHINEAS F. KING, OF CLEVELAND, OHIO, ASSIGNOR OF ONE-SIXTH TO
GEORGE HOYT, ONE-SIXTH TO WORTHINGTON HOYT, AND ONE-
THIRD TO J. D. CHAMBERS.

COTTON-GIN.

No. 819,893.

Specification of Letters Patent.

Patented May 8, 1906.

Application filed May 19, 1905. Serial No. 261,169.

To all whom it may concern:

Be it known that I, PHINEAS F. KING, residing at Cleveland, in the county of Cuyahoga and State of Ohio, have invented a certain new and useful Improvement in Cotton-Gins, of which the following is a full, clear, and exact description, reference being had to the accompanying drawings.

Cotton-gins of the roller type are exceedingly efficient machines when used with "short-staple" cotton. They are also probably the most efficient forms of cotton-gins in ginning "long-staple" cotton; but nevertheless when so used they cause the cotton to become kinked or knotted, thereby very greatly impairing its value. Much thought and labor have been expended in the effort to so modify the roller-gins that they would not act in the manner stated. These efforts have heretofore been without success, perhaps because it was never definitely determined what characteristic of construction present in such roller-gins caused the kinking of the long-staple fibers. I have discovered that the cause of this action is something inherent in a roller-gin—viz., the curved surfaces on the roller and the opposed knife-bars between which the fibers are drawn by the rollers. I have therefore devised a cotton-gin, which is shown in the drawings and hereinafter described, in which the cotton fiber is not drawn between two curved surfaces, but is drawn between two substantially parallel plane surfaces—viz., one fixed and one movable—for example, the plane side of a rotating disk and the plane face of an opposed knife-bar. The moving plane surface has much the same function as the periphery of the roller in the roller-gin, but it has not the defect above referred to in operating upon long-staple cotton. The cotton fiber in passing along with the moving plane surface and between it and the knife-bar remains straight and comes out of the machine without kinks or knots, whether the staple be long or short. The gin, as shown in the drawings in which this invention is embodied, has certain other advantages as compared with the roller-gins—to wit, the machine is more compact and less expensive to construct and operate. It has greater capacity than roller-gins of corresponding size and cost; and it is very easy to increase the ca-

pacity of the machines, or rather to build other machines having greater capacity, without much additional expense, because it is only necessary to lengthen the shaft and apply thereto one or more additional disks and associated mechanisms. In other words, one may make a machine of increased capacity by merely multiplying the parts necessarily found in the machine.

In the drawings, Figure 1 is a sectional side elevation of the cotton-gin embodying the present invention. Fig. 2 is a side elevation thereof. Fig. 3 is an end view from the right end of Fig. 2. Fig. 4 is a sectional plan view of some of the disks and their associated parts. Fig. 5 is an elevation in plane, indicated by line 5 in Fig. 4, except that the disks are not sectioned. Fig. 6 is a plan view corresponding with Fig. 4 of a modified construction, and Fig. 7 is a plan view corresponding with Fig. 5 of the same modified construction.

Referring to the parts by letters, A represents a shaft capable of rotating rapidly in suitable bearings on the frame B of the machine. To it are attached a plurality of ginning-disks C, which are preferably made of corundum, although any suitable material may be employed. This shaft and all but about one-quarter of these ginning-disks are inclosed within a casing D, preferably made of sheet metal. Secured upon the frame B is a hopper F, having at its bottom a discharge-opening f of variable size, the size being made variable by a sliding gate f', whose position is determined by a set-screw f''. Below this feeding-opening in the hopper is a movable feed-belt E, which runs over suitable rollers e and is provided with a plurality of pins e', which as the belt moves along in the direction of the arrow, Fig. 1, take hold of the cotton and carry it along and deliver it to the action of the gin-disks. The cotton as it is so carried along by said feed-belt is carried between pins or teeth K, which act as combs to straighten out and untangle the cotton fibers. These disks have plane end faces, and associated with each end face is a knife-bar h and an inclined plate g. The knife-bar is secured in a horizontal position close to and almost in contact with the end face of said disk on one side of the shaft A, and the vertical face of the knife-bar is par-

allel with the opposed face of the disk. The knife-bar h is far enough below the inclined plate g to allow the stripped cotton-seed to pass between them.

5 As appears from the drawings and as before stated, a plurality of disks are attached to the same shaft, and the opposed ends of adjacent disks are both utilized. It is therefore possible to construct the knife-bars associated with two adjacent end surfaces as parts of a single plate H and to likewise form the two inclined surfaces g , associated with the same end surfaces, on a single block G . The vertical partition b is a rigid part of the frame 10 and is slotted to accommodate the several disks, and it, together with the knife-plates H , form between each pair of disks an approximately triangular chamber from which the cotton cannot pass into the casing D except 15 by passing between the knife-bars and end faces of the disks. The blocks G are secured to the partition b , and they are sharpened along their upper edges g' and are widest at their bases. When the feed-belt E carries 20 the seed-cotton from the hopper, it delivers it into the narrowing spaces between the blocks and the adjacent disks, and as more cotton is so delivered it will be forced against the end faces of the disks by the inclined faces g . The 25 knife-plates H rest at one end upon the frame B and may be moved toward shaft A by means of set-screws m , supported by a bar M . The inner ends h' of said knife-plates are curved and rest upon the shaft A or 30 sleeves a upon said shaft. These plates are guided between ribs b' , secured to the frame, and are held down somewhat loosely upon the frame by the flanges b^2 upon said ribs. In 35 each plate H is a central opening h^2 between the knife-bars formed by the sides of said plate, and the seeds after the fiber is stripped from them feed through this opening into a discharge-spout J . In the preferred construction these disks C are widest at their 40 centers and are tapered toward their peripheries, so that they are narrowest at their periphery. The knife-bars forming the knife-plate are shaped so that they are parallel with the adjacent surface of the disks—that 45 is to say, this plate is narrowest near the shaft A . As a matter of fact, the knife-bars should be as close to the end faces of the disks as they can be without touching them. When the disks and the knife-plate are 50 tapered, as shown, they may be readily fitted to one another by forcing the knife-plate inward—that is to say, toward the shaft—until the disks accurately grind the knife-bars to fit.

55 The operation of the mechanism will be readily understood. The feed-belt carries the seed-cotton from the hopper and delivers it between the disks, and the inclined surfaces g guide the cotton against the end faces 60 of said disks. The end surfaces of these

disks adhere to the cotton fibers and pull them along between themselves and the adjacent knife-bars, thereby stripping said fibers from the seeds, which seeds when thoroughly stripped drop through the openings 70 in the knife-plates into the discharge-spout J . Because the knife-plates H rest loosely at their inner ends upon the shaft and at their outer ends are not held down firmly upon the frame said plates are free to vibrate slightly, and as a matter of fact they do vibrate up and down when the machine 75 is in use, and this vibration agitates the stripped seeds, so that they find their way into the openings in the knife-plates. After the cotton fiber has been carried along by the disks and past said knives and has been thoroughly separated from the seeds said fibers are thrown from the disks into the casing D , from which they are removed, as may be 80 necessary.

The reference-letters employed in connection with elements mentioned in the following claims are used merely to enable the reader to easily locate the parts referred to 90 and not with the intention of thereby limiting said claims to any particular form of such parts other than is necessary for the described co-operative action.

The modification shown in Figs. 6 and 7 95 differs from the construction shown in the other figures in one particular only—namely, that the opposite end faces of the disk are parallel with each other—that is to say, the disks are the same thickness in all parts instead of being widest at their centers and tapered toward their peripheries.

Having described my invention, I claim—

1. In a cotton-gin, the combination of a rigid movable member having a substantially vertical plane surface with a substantially horizontal knife-bar having a plane edge which lies close to and is parallel with the vertical plane surface of said movable member, means for moving said movable member in a vertical plane to cause its plane surface to move rapidly past the edge of said knife-bar, and means for forcing seed-cotton against the said plane surface of said movable member.

2. In a cotton-gin, the combination of a rigid disk C rotatable upon a horizontal axis, a knife-bar held close to the substantially vertical end face of said disk on one side only of the axis thereof, means for rotating said disk, 120 and means for feeding seed-cotton against the end face of said disk.

3. In a cotton-gin, the combination of a rotatable disk C , a knife-bar H held close to the end face of said disk, means for rotating said disk, an inclined plate above said knife-bar and adjacent to the end face of said disk, and means for feeding seed-cotton between said inclined plate and the end face of said disk.

4. In a cotton-gin, the combination of a ro-

130

tatable shaft, and a plurality of ginning-disks secured thereto, with a knife-plate located between each pair of adjacent disks and having its edges close to and parallel with the opposed end faces of said disks and having a central opening for the passage of the stripped seed.

5 5. In a cotton-gin, the combination of a rotatable shaft, and a plurality of ginning-disks secured thereto, with two knife-bars located between each pair of adjacent disks with their respective edges close to and parallel with the opposed end faces of said disks, and a wedge-shaped block secured between the disks and 15 a short distance above said knife-bars.

6. In a cotton-gin, the combination of a rotatable shaft, and a plurality of ginning-disks secured thereto, with a knife-plate located between each pair of adjacent disks and having its edges close to and parallel with the opposed end faces of said disks and having a central opening for the passage of the stripped seed, said plate being supported at its inner end by resting loosely upon said shaft and 25 being supported at its outer end upon the machine-frame.

7. In a cotton-gin, the combination of a rotatable shaft, and a plurality of ginning-disks secured thereto, with a knife-plate located 30 between each pair of adjacent disks and having its edges close to and parallel with the opposed end faces of said disks and having a

central opening for the passage of the stripped seed, said plate being supported at its inner end by resting loosely upon said shaft and 35 being supported at its outer end upon the machine-frame, and means for adjusting said knife-plate toward said shaft.

8. In a cotton-gin, the combination of a rotatable shaft, and a plurality of disks C secured thereto, with the slotted vertical partition extending down between said disks, the horizontal knife-bars *h*, and means for feeding seed-cotton into the space bounded by two disks, the partition *b* and the knife-bars. 45

9. In a cotton-gin, the combination of a rotatable shaft, and a plurality of disks secured to said shaft, which disks have their end faces of pyramidal form, with a knife-plate *H* supported in a horizontal position with its sides 50 respectively close to and parallel with the opposed end faces of said disks, on one side of their axis, said knife-plate having a central opening, and a wedge-shaped deflector between the disks and above said knife-plate, 55 and a partition to which said wedge-shaped block is secured and which has slots which embrace but do not touch said disks.

In testimony whereof I hereunto affix my signature in the presence of two witnesses.
